UNITED STATES PATENT OFFICE.

JACOB V. CLOSE, OF ROWAYTON, CONNECTICUT, ASSIGNOR TO ROBERT S. BARCLAY, OF ROWAYTON, CONNECTICUT.

COMBINED JOINTER AND RAKER.

No. 918,967.

Specification of Letters Patent.

Patented April 20, 1909.

Application filed June 6, 1908. Serial No. 437,087.

To all whom it may concern:

Be it known that I, JACOB V. CLOSE, a citizen of the United States, and a resident of Rowayton, in the county of Fairfield and 5 State of Connecticut, have invented a new and Improved Combined Jointer and Raker, of which the following is a full, clear, and exact description.

This invention relates to certain improvements in tools adapted for use by bricklayers in removing the superfluous mortar from between adjacent bricks and for smoothing the remaining mortar to give it a neat and finished appearance.

10 15 My invention involves a single tool, the opposite ends thereof being adapted for both uses above referred to. The parts of the tool which engage with the mortar are detachable from the body of the tool, so that different 20 parts having a different shape and size may be substituted in place thereof. The part of the tool used for jointing or pointing constitutes the handle for the tool while it is being used for raking.

25 Reference is to be had to the accompanying drawings forming a part of this specification, in which similar characters of reference indicate corresponding parts in all the figures.

Figure 1 is a top plan of a tool constructed 30 in accordance with my invention; Fig. 2 is a side elevation thereof; Fig. 3 is a top plan of a separate jointing member adapted to be used in place of the jointing member shown in Figs. 1 and 2; Fig. 4 is a perspective view 35 of the raking member shown in Figs. 1 and 2; and Fig. 5 is a perspective view of a raking member adapted to be used in place of the member shown in Fig. 4.

The specific form of my jointer and raker 40 shown in the accompanying drawings is composed essentially of three members, a body member 10, a raking member 11 and a jointing or pointing member 12. The body 10 is provided with a head 13 having a substantially flat under surface 14 of a width somewhat greater than the maximum width between the two courses of brick, and adapted to engage with the face of the brick work as the tool is drawn along. At the end of the 45 body opposite to said head there is provided an upwardly extending portion 15 bent at such an angle as to permit the jointing member to be grasped in the hand, to permit the under surface 14 of the head 13 to lie flat 50 against the brick work. The head 13 is pro-

vided with a passage polygonal in cross section and extending at substantially right angles to the under surface 14. At the intersection of this passage with the surface 14, the head is provided with a longitudinal 60 groove extending to the extreme end of the head and of a width substantially equal to the width of the passage above referred to. This passage and groove are adapted to receive my improved raking member 11 illustrated in perspective in Fig. 4. The raking member comprises a body portion 16 of substantially the same shape as the passage through the head 13, and is provided with an offset portion 17 adapted to fit within the 65 groove in the under surface of the head. At the outer end of the offset portion is the operating end 18 of the member. The raking member 11 fits within the groove and passage, with the under surface of the offset 70 75 80 85 90 95 100 105 110 115 120 125 130 135 140 145 150 155 160 165 170 175 180 185 190 195 198 199 convex or of any other suitable configuration depending upon the shape which it is desired to give the exposed surface of the mortar between the bricks. One end of the 5 jointer member is adapted to be rigidly secured to the body 10, any suitable form of connection being employed. As shown, the outer end of the body is provided with a socket and the end of the jointer member is 10 provided with a tongue or projection 20 adapted to be rigidly held therein by a suitable set screw 21.

A plurality of jointer members may be provided, varying in size and width, so as to 15 adapt the tool for use for brick work having varying distances between the several courses of brick. In Fig. 3 I have shown a jointer member 12^a substantially identical with that shown in Figs. 1 and 2, save that it is of some- 20 what greater width.

In the use of my improved tool a jointer member and a raker member are selected of a width dependent upon the width of the groove to be raked and pointed, and the 25 raker member is adjusted to extend below the surface 14 to the distance desired. By holding the tool substantially in the position shown in Fig. 2 with the operating end 18 between adjacent bricks, the tool is drawn 30 longitudinally to remove the mortar to the desired depth. The bricklayer then reverses the tool and uses the jointer member 12 for smoothing the remaining mortar.

Having thus described my invention, I 35 claim as new and desire to secure by Letters Patent:

1. A tool of the class described, comprising a body having a head at one end thereof provided with a surface extending substantially longitudinally of the tool, said head having an opening therethrough at sub-

stantially right angles to said surface and a groove extending from said opening to the end of said tool, and a raking member extending through said opening and having a laterally-extending portion disposed within said groove and an operating end extending downwardly from said laterally-extending portion and having a surface substantially in alignment with the plane of the end of the 45 head.

2. A tool of the class described having a body provided with a head at one end having a substantially flat surface, a raking member extending through said head and having an 55 operating end extending below said surface and presenting an outer surface substantially in the plane of the surface of the end of the head, said raking member being longitudinally adjustable through said head, and 60 means for securing said raking member in adjusted position.

3. A tool of the class described having a body provided with a head at one end having a substantially flat surface, a raking member extending through said head and having an operating end extending below said surface and presenting an outer surface substantially in the plane of the surface of the end of the head, said raking member being longitudinally adjustable through said head, means for 65 securing said raking member in adjusted position, and a handle rigidly secured to said body but detachable therefrom and adapted to serve as a jointer. 70

In testimony whereof I have signed my name to this specification in the presence of two subscribing witnesses.

JACOB V. CLOSE.
